COMBINED POTATO MASHER AND KNIFE

Alva Houston Elder, Ashland, Ky.
(% A. J. Derifield, Rte. 1, South Point, Ohio)

Filed Aug. 21, 1962, Ser. No. 71,395

Term of patent 14 years

(Cl. D44—29)

FIG. 1

FIG. 2

FIG. 3

FIG. 5

FIGURE 1 is a perspective view of a combined potato masher and knife, showing my new design; FIGURE 2 is a side elevational view; FIGURE 3 is a front elevational view; FIGURE 4 is a rear elevational view; and FIGURE 5 is a top plan view.

I claim:

The ornamental design for a combined potato masher and knife, as shown.
